COUNTER PASTING MACHINE

Charles Martin Bagshaw, Leicester, England, assignor to United Shoe Machinery Corporation, Flemington, N. J., a corporation of New Jersey

Application June 27, 1944, Serial No. 542,281
In Great Britain July 30, 1943

26 Claims.

(Cl. 12—80)

1

This invention pertains to improvements in machines for and methods of applying a coating to shoe parts and is illustrated herein, in its machine aspect, as embodied in an improved counter pasting machine of the type disclosed in an application Serial No. 512,924, filed December 4, 1943, in my name, and to which reference may be had for details not more fully disclosed herein.

In the above-mentioned application there is illustrated and claimed a machine for applying adhesive, hereinafter called paste, to a premolded counter in a semiautomatic manner, said machine being used in conjunction with heel-seat lasting machines to furnish freshly coated counters at a rapid rate and is such timed relation with the heel-seat pulling-over and lasting operations that a freshly coated counter will constantly be in readiness for the succeeding operation. The aforesaid prior machine includes a pair of oppositely disposed parallel applicator brushes, furnished with paste and between which the diverging legs of the counter are moved in succession. A reciprocating crosshead is provided for moving the counter linearly with respect to the applicator brushes, open end first, to advance one leg of the counter between the brushes, then to rotate the counter as the rounded end reaches the brush engaging the inner side of the counter, and then to continue the linear movement of the counter in the same direction, rounded end first, to draw the other leg between the brushes. The movement of the crosshead is then reversed and hence carries the counter back to its starting point, the linear and rotational movements of the counter being duplicated in opposite directions so that two coats of paste are applied. For reasons which appear in the prior application, it is desirable to omit the application of paste to the upper margins and especially to the inside and outside marginal surfaces of the legs of the counter adjacent to their ends. This was accomplished in the prior machine by arranging the supporting means so that it held the counter with one leg at an angle to its path of movement relative to the applicator, the angular position of the counter being such that the marginal portion of the counter leg adjacent to its advancing end lay outside the sphere of action of the applicator and hence this portion remained uncoated. In some instances, because of the angle at which the leg of the counter approached the applicator, there was some fuzziness between the coated area of the counter leg and the uncoated marginal portion thereof, due to the fact that the initial contact between the applicator and the counter was

substantially tangential. Hence, the applicator, which, as illustrated, is a brush, so lightly engaged the leg of the counter adjacent to the uncoated area upon initial contact that the thickness of the paste applied at this point was very thin.

An object of the invention is to provide an improved coating machine for progressively applying a coating to a piece of work, by relative movement between an applicator and a work holder, which will insure an adequate coating at one point in the progressive operation by increasing the pressure between the work and the applicator. By such an arrangement, it is possible to obtain a heavy coating of paste at, for example, the line of initial engagement between the applicator and a piece of work, such as a shoe counter.

In order to enable the progressive application of a band of coating material of uniform thickness which may be spaced from the edges of the work, thereby leaving a bare margin, the machine is arranged, in accordance with a feature of the invention, for relative movement between a work holder and an applicator and for additional movement between the work holder and the applicator in a direction different from the direction of progressive coating movement to bring the work and the applicator firmly together at one point, such as at the time of initial engagement between the two. As herein illustrated, the applicator is in the form of a driven rotary brush and the work carrier, movable in a predetermined path to present the leg of the counter substantially tangentially to that brush inside of a bare margin on the counter, is arranged to tilt the counter firmly against the brush at the point of initial contact and again adjacent to the point of separation between the brush and the counter.

As in the prior machine, the machine of the present invention includes two applicators, such as driven rotatable brushes, one of which is also movable bodily. One of the brushes is supplied with paste directly, and the other receives a supply of paste from the first brush during those periods when no work is passing between them. The bodily movable brush receives paste directly from a paste container herein, however, and in accordance with a feature of this invention, means is provided for extruding paste from the container onto the surface of the brush. As illustrated, this is accomplished automatically by an extrusion member associated with the container and operated by the movement of the counter holding and clamping means to force the

paste through a plurality of openings in the bottom of the container onto the surface of the applicator brush and in such timed relation with the movement of the counter holder that the paste is applied to the brush when the counter holder and clamping means is at its loading position and hence out of contact with the brushes.

Still another feature of the invention resides in manual means for extruding paste from the container independently of the aforesaid automatic means so that the brushes may be initially loaded with a sufficient quantity of paste to insure an adequate coating of the counter as the machine is started or at any point during the operation of the machine at which it appears necessary to furnish additional paste to the brushes.

In another aspect, invention will be found to reside in a method of coating the mid-portion of a work member so as to leave a bare margin which consists in bringing together such a work member and an applicator member by relative bodily movement to cause a contact between the work and the applicator and in then imparting movement to one of these members to increase the pressure of contact at one time during the progressive contacting movement between the members.

More specifically, the novel method consists in applying a coating to the mid-portion of a counter by imparting a bodily movement to the counter to bring it into engagement with an applicator at a point removed from the edge of the counter and in then imparting a secondary movement to the counter to increase the pressure between them.

Other features of the invention in addition to those above referred to, and including improved details of construction and combinations of parts, the advantages of which will be clear to those skilled in the art, will be hereinafter more particularly described with reference to the accompanying drawings, in which:

Fig. 1 is a side elevation of the front end portion of the machine with a crosshead which supports the counter, in its initial or loading position;

Fig. 2 is a horizontal section through a paste receptacle;

Fig. 3 is an elevation on a smaller scale, with parts broken away and in section, of the front end of the machine, showing the coaction of the applicator brushes with a counter;

Fig. 4 is a vertical section through the machine taken on the line IV—IV in Fig. 3 and showing both an extruding device in the receptacle and the coaction of one of the applicator brushes with the inside of the counter;

Fig. 5 is a fragmentary view taken in the same plane as Fig. 4 but with the counter holding means in a different position;

Fig. 6 is a fragmentary vertical section through the paste receptacle and with the extruding device in another position from that shown in Fig. 4;

Fig. 7 is an angular view of a counter the peripheral surfaces of which have been coated, leaving the upper and end margins bare; and

Fig. 8 is a plan view of the machine with the upper brush and the paste receptacle removed.

Referring to Figs. 1 and 3, the forepart of a rectangular channel-shaped frame 10 is shown fastened in a horizontal position upon the upper end of a vertical pedestal 12 which rises from the floor and forms a base for the machine. The rectangular frame 10 supports in operative rela-

tion, one to the other, means 14 for applying a coating of adhesive, hereinafter called paste, to a premolded counter C (Fig. 7) and means 16 for holding the counter and moving it progressively with respect to the applicator means in such a manner as to apply paste to both the inside and outside surfaces of the counter, as illustrated in Fig. 7, except for the inner upper margin 200 and the outer margin 202 extending forwardly from the back part, the inner end margin 204, the outer end margin 206, and the bottom flange 208, which are left free of paste.

The means 14 for applying the paste consists of a pair of juxtaposed brushes 18 and 20 (Figs. 1 and 3) mounted for rotation with parallel shafts 22 and 24, the latter being journaled in bearings 26 and 28, respectively, (Fig. 3). The bearing 28 is formed in an upwardly projecting bracket 30 fastened to the left side of the frame 10, as seen in Fig. 3. The bearing sleeve 26 for the upper brush 18 is pivotally mounted at 27, as in the prior application; at the top of an extension 29 of the bracket 30 so that its axis may be tilted in a vertical plane to permit movement of the upper brush 18 to and from the lower brush 20. The bearing 26 is normally urged to turn in a counterclockwise direction (as viewed in Fig. 3) about its pivot 27 by a spring-pressed plunger 32 which tends to hold the brush 18 away from the brush 20. Pulleys 34 and 36 are fixed to the shafts 22 and 24 and are connected, as will be seen by reference to the prior application, to a source of power (not shown herein) for rotating the brushes 18 and 20 in opposite directions, as indicated by the arrows in Fig. 1. The upper brush 18 is adapted to apply a coating of paste to the outside surface of the counter and is about six inches in diameter, having relatively long, flexible bristles which will conform readily to the shape of the counter. It rotates in a clockwise direction (Fig. 1) at about 60 R. P. M. The brush 20 is adapted to apply paste to the inside surface of the counter and is about two and one-half inches in diameter, having relatively long, flexible bristles which will conform to the inside of the counter. This brush rotates at about the same peripheral speed as the brush 18 in a counterclockwise direction, and it is to be observed that the shafts of the brushes are close enough together so that the bristles of the two brushes may be caused to overlap by an appreciable amount (Fig. 1). The brush 18 is furnished with paste from a receptacle 38 (Fig. 4) and the brush 20 receives paste indirectly from the receptacle by way of the brush 18 during those periods when no work is being passed between the brushes.

The receptacle 38 (Figs. 1 and 4) is mounted above the topmost point of the brush 18, in substantially tangential relation thereto, upon a shelf 40 which is fastened to an arm 42; the arm, in turn, being fastened to a post 44 by screws 46. The post 44 is bolted to a bracket 48 (Fig. 1) which, in turn, is bolted to the right side of the frame 10. A forked leg 41 which is fastened to the underside of the shelf 40 assists in guiding the shaft 22 as it moves up and down with respect to the lower brush shaft 24, the forked portion straddling an extension of the shaft 22, as seen in Fig. 3. In contrast to the prior machine, the bottom side of the paste receptacle 38 (Figs. 2, 4 and 6) has formed therein a plurality of small perforations 50 (shown exaggerated for clarity in Figs. 4 and 6) arranged widthwise thereof and occupying the central portion of the bottom near one end, and through which paste may be ex-

truded onto the surface of the applicator brush 18. Adjacent to the perforations 50, on the inside of the receptacle (Fig. 6) is a shoulder 52 which extends vertically from the bottom of the receptacle for the full width of the perforations, the shoulder having a horizontal surface 54 adjoining its vertical surface. Through the opposite end of the receptacle there is formed an opening 56 in which there is slidably mounted a flat valve plate 58 adapted to slide on the bottom of the receptacle to and from the aforesaid shoulder. At the inner end of the slide there is an enlargement 60 having a recess on its under side bounded by parallel side walls 62 (Fig. 2), a rear wall 64, and a top wall 66 which form with the bottom of the receptacle an open-ended rectangular chamber 68. The height of the chamber 68 is such that, as the valve plate is moved toward the front of the machine, i. e. the left in Fig. 4, the top and side walls will telescopically slide over the shoulder 52 adjacent to the perforations in the bottom of the receptacle. With the aforesaid construction, when the valve plate 58 is withdrawn to the right to the position shown in Fig. 6, the paste in the receptacle will gravitate to the bottom and fill the open-ended chamber at the end of the valve plate. Upon movement of the valve plate 58 to the left, the open end of the chamber 68 will be closed by the shoulder 52 and, as the movement to the left is continued, the volume of the chamber will decrease and the paste therein will be extruded through the perforations 50 directly upon the applicator brush 18. A rectangular, sleeve-like partition 70, having top and side walls adapted to surround the slide valve adjacent to the opening through which it slides in the end of the receptacle, prevents escape of the paste through the end of the receptacle. The aforesaid slide valve 58 is operated automatically to extrude paste at the proper time for application to the applicator brush 18 when the latter is not engaging a counter, or alternatively manually. The specific construction of the means for operating the valve will be described hereinafter.

While the slide valve 58 for extruding the paste from the receptacle is ordinarily automatically operated, as will appear further on, it may be desirable to load the applicator brush 18 with paste prior to setting the machine in motion, or at other times during the operation of the machine, independently of the automatic means. Such independent application of paste to the brush is provided for by manually operable means. This means includes a pair of rods 72 (Fig. 2) at opposite sides of the receptacle adapted to slide in bosses 74 formed at the lower corners of the receptacle. The rods are connected at their opposite ends by horizontal bars 76 which may be grasped by the operator and afford means for sliding the rods longitudinally within their bosses. One of the bars 76, namely, that shown at the right in Fig. 2, is fixed to the free end of the slide valve which projects from the receptacle. By grasping one of the bars and pushing the rods from right to left, as seen in Fig. 6, the valve may be actuated to extrude paste. It is apparent that the positive extrusion of a given quantity of paste from the receptacle each time, either by the automatic means or by the manual means just described, permits applying a definite quantity of paste to the applicator brush regardless of the temperature or viscosity of the paste and thus insures a uniform supply to the applicators at all times.

The counter C, as shown in Fig. 7, is preformed

and has diverging legs joined by a rounded back part, and in the illustrated machine, as in the prior machine, movable supporting means 16 is provided for holding the counter and moving it, open end first, in a linear direction to advance one leg between the brushes 18 and 20 until the inner surface of the rounded back part substantially engages the brush 20, then to rotate the counter to bring the other leg into a corresponding position, and, finally, to resume the linear movement of the counter in the same direction, rounded end first, to draw the other leg between the brushes. As in the prior machine, the counter holding means 16 includes a rotatable V-shaped support 80 (Figs. 3 and 8) having a groove 82 to receive the bottom flange 208 (Fig. 7) of a counter C, and a clamping means 78 to grip the upper margins 200, 202 thereof. This clamping means 78 is rotatable in step with the support 80 and comprises clamps 86 (Fig. 1) to hold the upper margins of the legs of the counter against a V-shaped block 84. In order to prevent the application of paste to the inner margins 204 of the curved portions near the ends of the legs, the counter holding means 16 is constructed to hold the legs of the counter at an angle of about 20° to the horizontal and, as a result, these margins 204 of the counter lie outside the field of action of the brush 20 and, when the ends of the legs are moved across the brush, those portions do not engage it. In order also to preserve the end margins 206 of the outer surfaces of the legs free from an application of paste, the brush 18, adapted to apply paste to the outer surface of the counter, is moved up and down in timed relation with the movements of the counter to bring it into contact with the legs back of the marginal end portions 206 thereof.

While the angular position of the counter with respect to its direction of travel causes the end marginal portion of the advancing leg to pass above and beyond the applicator brush 20 without receiving an application of paste therefrom, the initial contact between the two is very light, due to the fact that the applicator brush is composed of a plurality of flexible bristles which extend radially from the center of rotation of the brush. In other words, since the surface of the counter approaches the applicator substantially tangentially thereto, it is found that the pressure is so light when the surface of the counter first contacts the brush that there is substantially no application of paste. As a result, there is no clear line between the uncoated area 204 at the marginal end of the leg and the coated area at the rear of this marginal portion. This is undesirable because the adhesive bond between the counter and the lining and upper material at this point would be weakened by this lack of paste and would constitute a starting point for the lining material to pull away from the counter. The improved machine illustrated herein overcomes this undesirable feature by insuring an application of paste at the point of initial contact which will be of equal weight to that which will be applied to the remainder of the counter, and this will be accomplished, as will appear hereinafter, by imparting a secondary movement to the counter holder and clamping means, as initial engagement is established between the counter and the applicator, to press the counter into intimate contact with the applicator.

The primary and secondary movements of the counter transversely of the means for applying

paste thereto, that is, the brushes 18 and 20, are imparted thereto by the holding means 16 comprising the counter support 80 (Fig. 3) and the counter clamping means 78, which are rotatable about a common axis. The counter holding and clamping members are supported for movement as a unit on the uprights 91 and 92 of a cross head 94 which moves in a path contiguous to the applicator brushes to advance one leg of the counter between the applicator brushes, then dwells while the counter is rotated to bring the other leg into position between the applicator brushes, and then moves to withdraw this latter leg, thereby to coat the entire surface of the counter. The crosshead 94 is reciprocated to carry the counter past the applicator first in one direction and then in the other direction.

The axes of rotation of the counter clamping means 78 and the support 80 are coincident, the counter support 80 being fixed to a horizontal sleeve 83 supported on the upright 91 (Fig. 3) for rotation about an axis coinciding at that time with the axis of the brush 20, and the counter clamping means 78 being fixed upon a horizontal shaft 88 which is rotatably mounted in a split bearing 90, the latter being formed integral with the upright 92 on the crosshead 94. The split bearing 90 is provided with a pair of bosses 96 which are joined by a bolt 98, the bolt passing through a spring 100 and then loosely through an adjacent boss and being threaded into the other. By rotation of the bolt, the elements of the bearing may be drawn together about the shaft 88 yieldably to grip the shaft, the adjustment of the bolt affording means for varying the frictional resistance to rotation of the shaft.

The crosshead 94 which carries the counter support 80 and the clamping means 78 is mounted for movement transversely of the applicator brushes 18 and 20 upon a pair of horizontally disposed parallel rods 102 (Fig. 8), the rods being supported at their opposite ends at the front and rear ends of the rectangular frame 10. The transverse or linear sliding movement of the crosshead 94 along the rods 102 from front to rear moves the counter from its initial or loading position at the front of the machine at the left in Fig. 1, with its open end toward the right, toward the applicator brushes with the upper leg disposed at an angle of about 20° to the horizontal. Linear movement of the crosshead with the counter in this position brings the aforesaid leg into contact with the brush 20 which applies a coating to the inside of the counter at a point back of its leading edge, as will be seen by reference to Fig. 5, since the leading edge and the marginal portion 204 adjacent thereto pass above and beyond the brush without making contact with its surface as the counter is moved horizontally to the right toward the brush. Hence, this marginal portion remains uncoated.

At the moment that contact is established between the counter and the applicator, as shown in Fig. 5, and, in contrast to the prior machine, a secondary movement, which comprises a further partial rotation of the counter holding means 16 about its axis, takes place in such a manner as to force the surface of the counter into intimate contact with the applicator brush, as illustrated in Fig. 4. After this secondary movement takes place, the crosshead continues its linear movement until the brush 20 engages the closed, rounded end of the counter, whereupon means to be described causes a half-rotation of the counter which brings the other leg of the counter

into a position reversely inclined to that of the first leg of the counter, that is, so that this latter leg makes an angle of about 20° to the horizontal. After this rotation is completed, the crosshead resumes its linear movement in the same direction and the second leg is drawn between the brushes and disengages the lower brush 20 at a point which precedes the trailing end of this second leg. Hence, a marginal portion 204 on the second leg is also left uncoated.

During the coating of the inner surfaces of the legs, the outer surface is also coated, the upper brush 18 being moved up and down in timed relation with the movement of the counter so that contact is made with the first leg at a point spaced from the advancing end and substantially opposite to the contact of the brush 20 with the inner surface of the leg, and contact is broken, by raising the brush 18 at a corresponding point on the opposite leg.

As in the earlier machine, the travel of the crosshead 94 and the partial rotation of the counter holding means 16 during that travel is effected by means of a chain drive comprising chains stretched from front to rear of the machine associated respectively with the counter holding means 80 and the counter clamping means 78. One chain 112, which is at the left side of the machine, the top side in Fig. 8, has both its end portions partially wrapped around a pulley 110 and secured thereto. This pulley, as may be seen from Fig. 3, is mounted on the hollow shaft 83 which carries the counter holder 80. The pulley 110 has two grooves and the ends of the chain are fastened in these grooves. The chain 112 passes over a pulley 108 at the front end of the machine, extends along (Fig. 1) the frame to the under side of a sprocket 109 at the rear end and then passes around the sprocket and back to the pulley 110. The pulley 108 is supported on a stud 106 carried by a post 104. A reversible belt drive 115 (Fig. 8) is connected with the sprocket at the rear end of the machine and is adapted to be controlled as to direction of rotation by a belt shifter 117 which may be moved by means of a lever 119 connected to a manually operable rod 180 (Fig. 1) or by suitable contact between the crosshead 94 and pieces such as the lever 119 associated with that rod. As a consequence, the crosshead travels from the position shown in Fig. 1 to a position at the other end of the machine and then the belt drive is reversed and the crosshead is returned to the starting position. A similar chain 113 along the right side of the machine, the near side in Fig. 1, is associated with a similar grooved pulley 111 mounted on the shaft 88 of the counter clamping means 78 and passes over a pulley 114 on a post 116 and a sprocket 121 at the rear end (Fig. 8).

In the prior machine, the counter holding and clamping means are rotated at one point in the linear movement of the crosshead when the rounded, closed end of the counter reaches the applicator brushes. This is accomplished by a pair of levers 120 and 122 (Fig. 1) which are pivotally fastened to the frame 10 at 124 and 126, the lower ends being urged toward each other by a spring 128 which is fastened between them. The upper ends of the levers bear on the under-side of a horizontal bar 130 (Figs. 1 and 8) which is fastened to the crosshead and moves therewith, and are adapted to engage notches 132 formed in the underside of the bar. During movement of the crosshead toward the rear of the machine, 75 that is, to the right as seen in Fig. 1, the lever

122 will engage the right-hand notch 132 and arrest the linear movement, whereupon continued movement of the chains 112 and 113 will start rotation of the counter holding and clamping means 16 about the axis of the sleeve 83 (Fig. 3). In a disk 137 fast on this sleeve is a pair of stop screws 134 and 134' (Fig. 4) threaded through radial lugs 136 formed integral with the disk. After approximately a half rotation clockwise, as seen in Fig. 4, of the counter holder, the screw 134' will strike the lever 122 and push it down out of the notch 132, whereupon the crosshead will continue its linear movement to the rear of the machine. The movement of the counter holding and clamping means during its approach to the brushes and after it has passed beyond the applicator brushes is restricted to linear movement by the frictional resistance to rotation of said holding and clamping means afforded by the split bearing 90 drawn about the shaft 88. When the lever 122 rises into the notch 132 and temporarily stops the linear movement of the crosshead toward the center of the machine, the frictional resistance to rotation of the shaft 88 in its bearing 90 is overcome and rotation takes place until the screw 134' moves the lever 122 out of the notch. On the reverse movement of the crosshead from the rear to the front of the machine, that is, from right to left as seen in Fig. 1, the lever 120 performs a similar function so that the counter is again rotated as it passes the applicator brushes. A screw 135 on the disk 137 then abuts the top of the bar 130 and determines the initial position of the counter holding means 16 with the top of the counter leg at an angle of 20° to the horizontal, as before described.

In the improved machine herein described, means is provided for imparting a partial rotation to the counter holding means 80 and the clamping means 78 just before they reach the above-mentioned means 122 for producing the approximately half rotation of the counter in order to reverse their direction of movement and coat the trailing leg. This means is similar to the aforesaid means and, as illustrated herein, comprises a pair of yieldable levers 138 (Fig. 1) pivotally mounted at 140 on the frame of the machine in positions symmetrical to the brush shaft 24. Each lever has a cam surface 142 which occupies a position in the path of movement of the counter holding means so that, as a counter approaches the applicator brushes, the screw 134 carried by the disk 137 strikes the cam surface of one of the levers 138 and momentarily resists the linear movement of the crosshead. A partial rotation of the counter holding and clamping means immediately takes place. Since the period of contact between the lever and the screw is very short, the rotation is slight, but is sufficient to force the counter into contact with the applicator brush, that is, from the position indicated in Fig. 5 to that indicated in Fig. 4. The crosshead then continues its linear movement toward the applicator and when the lever 122 falls into the notch 132 a "half" rotation of the counter holding and clamping means takes place, as previously described. In its reversed position, the counter holding and clamping means continues on by or beyond the applicator brushes and the screw 134' strikes the second lever 138 but, since this lever is yieldable in the direction of motion of the counter holding and clamping means, the screw passes by the lever without producing further rotation of the counter holding and clamping means. On the reverse direction

of movement of the counter holding and clamping means, this second lever 138 will strike the screw 134' and produce a partial rotation in the reverse direction of the counter holding and clamping means so that the opposite leg of the counter is also insured an adequate application of paste at its initial contact with the brush 20. The lower ends of the levers 138 are extended and joined together by a pin 144 upon which there is mounted a coil spring 146 (Fig. 4), the latter being disposed between the levers on the pin, thereby permitting movement of the upper ends away from each other. To prevent movement of the upper ends of the levers 138 toward each other when the screws 134, 134' on the disk 137 strike them, as in Fig. 5, adjustable stop screws 148 are provided which are threaded through a bracket 150 fastened to the upright 30. By adjustment of these screws 148 and the screws 134, 134' in the disk 137, the amount of rotation of the counter holding and clamping means may be varied. The pin 144 is kept in place by cross pins outside of the lever ends.

As in the prior machine, the upper brush 18 is so mounted that it may be moved into and out of contact with the legs of the counter in timed relation with the movement of the counter transversely thereof. To permit such movement, as heretofore described, the upper brush 18 is mounted in the sleeve bearing 26 (Fig. 3) which is tiltable to and from the lower brush 20 about a horizontal pivot 27. The movement of the brush 18 to and from the brush 20 is controlled by the combination of the spring-pressed plunger 32 and a bar cam 152 (Fig. 1), the bar cam being fastened to the upper ends of a pair of vertical posts 154 which, in turn, are set into recesses formed in the sides of the post 92 on the near end of the crosshead 94, as seen by reference to Fig. 1, and held there by screws 156 and a through bolt 158. As will be seen by reference to Fig. 3, the shaft 22 extends through from the back of the brush 18 to the front thereof and has mounted thereon a freely rotatable sleeve 162 which is held against the under surface of the bar cam 152 by the spring-pressed plunger 32 which urges the bearing sleeve 26, and consequently the shaft 22 of the brush 18, in a counterclockwise direction about its pivot. The lower surface of the cam 152 is so shaped that, when the crosshead is at its initial or loading position (Fig. 1), that portion of its surface designated *a* holds the brush 18 in engagement with the brush 20 in opposition to the spring-pressed plunger 32 so that the brush 20 will receive paste from the brush 18. When the machine is started, the cam 152 moves to the right, as seen in Fig. 4, and the sleeve 162 follows the upward slope of the surface marked *b* so that, when the leading end of the counter is approximately adjacent to the entrance side of the brushes, the upper brush 18 will have risen to the position spaced from the brush 20, as shown in Fig. 4. Hence, the brush 18 is separated from the brush 20 and it does not contact the leading end of the counter. At this position, the sleeve 162 occupies the portion *c* of the bar cam. Further movement of the crosshead forces the sleeve 162 downward by reason of its engagement with the downwardly sloping surface *d* of the cam so that the brush 18 is brought into engagement with the outer surface of the counter after the end margin 206 thereof has passed and, at the portion *e*, the brush 18 is held in a fixed position during the rotation of

the counter as its closed end is coated. As the other leg of the counter is withdrawn from between the brushes, the brush 18 is allowed, by the sloping surface *f*, to rise out of contact with the counter, just as the trailing marginal portion 206 of the leg reaches the brushes. On the return movement of the crosshead, the brush 18 is actuated in the same manner by the portions 10 *f*, *e* and *d* to again treat the outer surface of the counter, while leaving the end margins bare.

The bar cam 152 which moves with the crosshead on which the counter holding and clamping means is mounted and which moves the upper applicator brush 18 to and from the paste container is provided at its right end, as shown in 15 Fig. 4, with novel means for operating the extruding valve. This comprises an extension 164 having an upright arm 166 fixed thereto, the arm having a passage 168 therein for the reception of a horizontal rod 170, the latter being attached to the valve slide 58. As will be seen, the end of the rod 170 is threaded into the horizontal bar 20 76 and is locked in place by a nut 172. Between the nut 172 and the upright arm 166 there is placed a coil spring 174. At the free end of the 25 rod 170 there is placed another coil spring 176 which is prevented from sliding off the end of the rod by a collar 178 fixed to the end of the rod. By the aforesaid construction, when the counter holding and clamping means is at its initial or 30 loading position at the front of the machine, the bar cam 152 to which the aforesaid arm 166 is fastened will be at its extreme left-hand position and will yieldably force the valve plate 58, as illustrated in Fig. 4, toward the shoulder 52, thereby 35 to extrude paste from the bottom of the receptacle through the perforations 50 onto the surface of the upper applicator brush 18. At this particular time, no work is passing between the applicator brushes and, since these brushes are rotating rapidly, the extruded paste will be delivered evenly by the top brush 18 to the lower brush 20 and, when the counter holding and clamping means begins its movement to the right with a 40 fresh uncoated counter therein, the brushes will be loaded with paste for application to the surface of the counter. As the counter holding and clamping means proceeds to the rear of the machine, the bar cam carrying the arm 166 will draw the rod 170 toward the right, thus pulling the valve plate 58 to the right so that it occupies a 45 position, as shown in Fig. 6, in which a fresh quantity of paste will gravitate into the chamber. The springs 174 and 176 yieldably permit full travel of the crosshead 94 without the necessity of exact adjustment of the contact between the arm 166 and the stop portions of the rod 170. Upon return movement of the counter holding and clamping means to the left, that is, to the 50 front of the machine again, another quantity of paste will be extruded.

Having inserted the bottom flange of a counter in the groove 82 of the support 80 (Fig. 3) and upper margins of its legs beneath the clamps 86 (Fig. 1) of the clamping means 78, the machine is set in operation by pulling forwardly on a rod 180 (Fig. 1), as in the previous machine, whereupon the crosshead 94 moves rearwardly, or to the right as shown in Figs. 1 and 8. During the initial movement of the crosshead, the counter holding and clamping means 16 occupies the position shown in Fig. 1, in which the upper leg of the counter makes an angle of substantially 20° with the horizontal. As the crosshead advances, open end first, the bar cam 152 moves forwardly and

allows the upper applying roll 18 to rise away from the lower roll 20 so that the end of the advancing leg of the counter moves between the brushes without contacting the same. As the leg continues its movement between the brushes, the inner surface of the leg begins to contact the brush 20 back of the uncoated margin 204 thereof, as shown in Fig. 5, and at this point the counter clamping and holding means 16 is given a partial rotation by reason of the contact of one of the screws 134 with one of the levers 138 so that the counter is brought positively into contact with the brush, as shown in Fig. 4. Simultaneously, the upper brush is brought into contact with the outside surface of the counter at substantially the same point thereon with relation to the end of the counter. The longitudinal movement of the crosshead continues until the rounded inner end of the counter comes into contact with the smaller brush 20, whereupon a complete reversal of the position of the counter takes place by engagement of the lever 122 with the rear notch 132 in the under side of the member 130. After reversal of the counter, the opposite leg is drawn between the brushes until, near the end of the movement of the crosshead, the upper brush 18 is lifted by the spring plunger 32 from the outside surface of the counter so that no cement is applied to the outside margin 206 near the end of the leg. Since the counter in its reversed position occupies the same angle with respect to the horizontal as it did in its initial position, the inside of the leg of the counter remains uncoated as it leaves the sphere of action of the brush 20. As in the previous machine, automatic means is provided for reversing the motion of the crosshead so that it travels to the front of the machine, or to the left as seen in Fig. 1, and during this return movement, the counter goes through the same partial rotations and tilting movements that it did during the rearward movement, thus insuring a positive application of cement on the inside surface of the opposite leg adjacent to its end.

During the travel of the crosshead from and to the front of the machine, the upper brush 18 is supplied with paste from the container 38 positively by means of the valve 58. This valve is operated by the motion of the crosshead and, 50 when the crosshead is at the extreme left or front end of the machine, as seen in Fig. 4, the valve is completely closed. As the crosshead moves toward the right, the valve remains closed until the arm 166, which is carried by the bar cam 152, 55 comes into engagement with the spring 176 on the rod 170, whereupon the valve is pulled open to the position shown in Fig. 6 and paste gravitates to the bottom of the receptacle, filling the chamber 68. Upon the reverse or return movement of the crosshead to the front of the machine, the valve is closed to extrude the paste by engagement of the arm 166 with the spring 174. If the operator finds that enough paste is not being delivered to the brushes, he may grasp one of the 60 horizontal bars 76 and, by moving it backwardly and forwardly, extrude an extra quantity of paste on the brush 18.

Having thus described my invention, what I claim as new and desire to secure by Letters Patent of the United States is:

1. In a machine for coating a piece of work, a work carrying holder supported for movements of translation, an applicator, means for effecting relative movement of translation between the work holder and the applicator to apply a coating

progressively along a piece of work held in the work holder, and means for increasing the pressure between the work and the applicator during at least a portion of the time of contact between the work and the applicator.

2. In a machine for coating a shoe part, an applicator, a work holder supported for bodily movement past the applicator, means for effecting relative movement between the work holder and the applicator progressively to coat a portion of the work spaced from the edges thereof, and means for increasing the pressure between the work and the applicator at one point in said progressive movement.

3. In a counter pasting machine, an applicator, a movably mounted work holder, means for moving said holder to carry the counter into engagement with the applicator at a point spaced from the edge of the counter, and means for increasing the pressure between the counter and the applicator substantially at the time of initial contact between the two.

4. In a counter pasting machine, a yieldable applicator, a holder for a counter, means for moving the holder in one direction to bring one leg of the counter into engagement with the applicator at a point spaced from the end of the leg and then progressively to coat a surface of the counter, and means for producing relative movement between the applicator and the holder in a direction different from the direction of movement of the work to press the counter against the applicator substantially at the beginning of the coating operation.

5. In a counter pasting machine, a yieldable applicator, a movable carrier, a holder for a molded counter tiltably mounted on said carrier, means for moving the carrier to bring one leg of the counter into engagement with the applicator at a point spaced from the end of the leg and continuing the movement of the carrier to extend the coating, and means for tilting the holder to increase the pressure between the counter leg and the applicator.

6. In a counter pasting machine, a yieldable rotary applicator, a movable carrier, a holder for a molded counter tiltably mounted on said carrier, means for moving the carrier in a predetermined path to bring one leg of the counter into substantial tangential engagement with the applicator at a point spaced from the end of the leg, and means for tilting the holder to increase the pressure between the counter leg and the applicator as the movement of the carrier is continued.

7. In a counter pasting machine, a yieldable rotary applicator, a movable carrier, a holder for a molded counter tiltably mounted on said carrier, means for moving the carrier to bring one leg of the counter into engagement with the applicator at a point spaced from the end of the leg, means for tilting the holder to increase the pressure between the counter leg and the applicator as the movement of the carrier is continued, and means for imparting a half rotation to the counter holder.

8. In a counter pasting machine, an adhesive applicator, a counter holder, and means for moving the counter holder, in a path contiguous to the applicator in such a manner that one leg of the counter is tilted at an angle to the path of movement and with its marginal portion at its leading end lying out of the sphere of action of said applicator, until said marginal portion has passed beyond the applicator and for then tilting

said holder to carry said leg toward the applicator thereby to establish firm contact between the surface of the counter and the applicator adjacent to said uncoated marginal portion.

5. In a counter pasting machine, an adhesive applicator, a counter holder, means for moving the counter holder, in a path contiguous to the applicator in such a manner that one leg of the counter is tilted at an angle to the path of movement and with the marginal portion of said leg lying out of the sphere of action of said applicator, until said marginal portion has passed beyond the applicator, and means for then tilting said holder to carry said leg toward the path of movement to decrease said angle thereby to bring the leg into intimate contact with the applicator at the instant of its initial engagement therewith.

10. In a pasting machine, an adhesive applicator, a work holder, means for producing relative movement therebetween to establish initial contact between the surface of the work and the applicator inwardly of the marginal portion of the work adjacent to its leading end and means for producing a secondary movement between said holder and applicator to bring said contacting portion into more intimate engagement with the applicator.

15. In a counter pasting machine, an adhesive applicator, a rotatable counter holder, movable means for bringing together a counter in the holder and the applicator to establish initial contact between them and then to cause progressive coating of the counter, and a cam for tilting the holder at a predetermined point in said progressive coating.

20. In a counter pasting machine, an adhesive applicator, a rotatable counter holder, movable means for bringing together a counter in the holder and the applicator to establish initial contact between them inwardly of the marginal end portion of the counter, and a cam lying in the path of the counter holder, said cam being cooperable with means on said holder to cause a partial rotation thereof in a direction to tilt the counter toward the applicator at the moment of initial contact.

25. In a counter pasting machine, an adhesive applicator, a rotatable counter holder, means for bringing together the counter holder and the applicator in a manner to establish initial contact between the surface of the counter and the applicator inwardly of the marginal portion adjacent to the leading end, a cam lying in the path of movement of the counter holder, and means on said holder cooperable with the cam to cause a partial rotation of the holder in a direction to tilt the counter toward the applicator at the moment of initial contact, said last-named means being adjustable to govern the position of engagement of said cam and means.

30. In a counter pasting machine, an adhesive applicator, a tilttable counter holder, means arranged to move the counter holder bodily in a path contiguous to the applicator first in one direction and then in another direction to advance first one leg and then the other toward the applicator and arranged to hold the advancing leg tilted at an angle to the path of movement with its marginal portion adjacent to its end lying outside the range of the applicator, means for imparting bodily movement to the counter holder, and means for tilting the counter holder as the marginal portion of each leg moves beyond the applicator to cause the holder to press the

15

counter, adjacent to its marginal portion, firmly against the applicator.

15. In a machine for coating a piece of work, a work holder, an applicator, means for effecting relative movement between the work holder and the applicator to bring them intermittently into coating relation, a receptacle for coating material, and means responsive to said relative movement for extruding coating material from the receptacle on the applicator.

16. In a machine for applying paste to a piece of work, a work holder, an applicator, means for moving the work holder to carry the work into contact with the applicator, and means for extruding paste from the receptacle on the applicator after the presentation of the piece of work.

17. In a machine for applying adhesive to a counter, a reciprocatory carrier for the counter, an applicator, a receptacle arranged to supply adhesive to the applicator, a reciprocatory extruding device in the receptacle, and means responsive to the reciprocatory movements of the carrier for operating said extruding device.

18. In a machine for applying adhesive to a counter, a counter holder, an applicator, means for bringing together the holder and applicator in a manner to coat the surface of the counter, means comprising a receptacle adjacent to the applicator for supplying adhesive to the surface thereof, and means for extruding adhesive from said receptacle onto said applicator, said last-named means being actuated by the first-named means.

19. In a machine for applying adhesive to a counter, a holder, an applicator, means for bringing together the holder and applicator in a manner to coat the surface of the counter, means for supplying adhesive to the surface of the applicator, said means comprising a receptacle adjacent to the applicator, a valve having a chamber and mounted for movement in said receptacle, means in said receptacle cooperable with the valve chamber to confine a quantity of adhesive and upon relative movement between the two to extrude adhesive from the receptacle, and means for actuating the valve at a predetermined time to bring about extrusion of the adhesive, said last-named means being actuated by said first-named means.

20. In a machine for applying adhesive to a counter, a holder, an applicator, means for bringing together the holder and applicator in a manner to coat the surface of the counter, and means for supplying adhesive to the surface of the applicator, said means comprising a receptacle adjacent to the applicator, a valve in said receptacle operable to force adhesive in said receptacle onto the applicator, and means associated with the first-named means to move said valve to an adhesive extruding position after the holder and applicator have separated.

21. In a machine for applying adhesive to a

16

counter, a holder, an applicator, means for moving the holder in a path contiguous to the applicator, a movable cam, means for moving the applicator in timed relation with the movement of the holder to bring the applicator into engagement with the counter at a predetermined time, an adhesive receptacle, means operable to extrude adhesive from the receptacle onto the applicator, and means mounted on said cam and movable thereby for yieldably actuating said last-named means.

15. 22. In a machine for applying adhesive to a counter, a holder, an applicator, means for bringing the holder and applicator together in a manner to coat the surface of the counter, a receptacle for adhesive adjacent to the applicator, automatic means for extruding adhesive from the receptacle onto the applicator, and manual means for actuating said extruding means independently of said automatic means.

16. 23. That method of progressively coating the mid portion of a work member leaving a bare margin adjacent thereto, which consists in bringing together a work member to be coated and an applicator member by relative bodily movement one with respect to the other to cause a contact of the applicator member with an intermediate portion of the work member, and imparting a movement to one of the members to increase the contacting pressure at one time during the progressive engagement between the members.

17. 24. That method of applying a coating to the mid portion of a counter while leaving an uncoated margin adjacent thereto, which consists in imparting a bodily movement to the counter to bring it into engagement with an applicator at a point removed from the edge of the counter, and then imparting a secondary movement to the counter to increase the pressure between the two.

18. 25. That method of applying a coating to a counter by means of a yielding applicator, which consists in carrying the counter bodily into engagement with the applicator to effect contact therewith at a point removed from the edge of the counter, and tilting the counter as it engages the yielding applicator to increase the contact pressure between the two.

19. 26. That method of applying a coating to a counter by means of a yielding applicator, which consists in carrying the counter bodily into engagement with the applicator to effect contact therewith at a point removed from the edge of the counter, tilting the counter as it engages the yielding applicator to increase the contact pressure between the two, continuing the bodily movement of the counter to carry the coating to a point spaced from the opposite end thereof, again tilting the counter into firm engagement with the applicator, and then carrying it away from the applicator.

CHARLES MARTIN BAGSHAW.
